(57) **CLAIM**

The ornamental design for a notebook computer as shown and described.

DESCRIPTION

FIG. 1 is a rear top perspective view of a notebook computer showing our new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The even-dash broken lines illustrate portions of the notebook computer that form no part of the claimed design. The dot-dash broken lines define a bounded area within the claimed design. This claimed area within the dot-dash broken lines extends to the dot-dash broken lines, but does not include the broken lines.
